UNITED STATES PATENT OFFICE.

CHARLES A. KELL, OF ELKHART, INDIANA.

REAMER.

Application filed June 29, 1921. Serial No. 481,302.

To all whom it may concern:

Be it known that I, CHARLES A. KELL, a citizen of the United States, residing at Elkhart, in the county of Elkhart and State 5 of Indiana, have invented new and useful Improvements in Reamers, of which the following is a specification.

This invention relates to boring or drilling tools, and particularly to reamers, having for its primary object to provide a tool of such construction as to obviate chattering when in use.

A further object of the invention is to provide a reamer wherein means of an improved nature is employed for enabling the cutting blades thereof to be adjusted radially of the reamer, whereby the cutting diameter of the tool may be increased or diminished as desired.

20 A still further object of the invention is to provide a reamer of the character stated having improved means for creating the adjustments as stated, and wherein the cutting blades are at all times held under a predetermined degree of pressure.

A still further object of the invention is to provide a reamer of the character specified which is of simple construction, which employs comparatively few simple and 30 readily assembled parts, which has its parts so constructed and assembled as to minimize the opportunity for wear, breakage or derangement, which may be quickly and easily adjusted to obtain the desired cut, and which 35 will prove thoroughly practical and efficient in use.

With these and other objects in view, the invention consists of the features of construction, combination and arrangement of parts, hereinafter fully described and claimed, reference being had to the accompanying drawings, in which:—

Figure 1 is a side elevation, parts in section, of a reamer embodying the invention, 45 Figure 2 is an elevation of the outer end of the reamer,

Figure 3 is a similar view of the inner end of the reamer,

Figure 4 is a sectional view of the coupling sleeve,

Figure 5 is a side elevation of the reamer head removed from the shank,

Figure 6 is an elevation of the outer end of the said head,

55 Figure 7 is an elevation of the spring

used to exert pressure upon the blade holders,

Figure 8 is a face view of one of the blade holders,

Figure 9 is a side elevation of one of the 60 blade holders, and

Figure 10 is an end elevation of one of the blade holders.

Referring now more particularly to the drawings, 11 indicates the shank of the 65 reamer, the latter being circular in cross section and of one diameter throughout a part of its length, having threads 12 upon its exterior for a substantial portion of its length, and being squared as at 13 at its inner end to enable the same to be applied to a machine. This shank tapers toward its outer end as shown, the walls of the tapered portions being smooth and straight throughout the entire circumference of the shank, 70 and the said tapered portion extending nearly to the outer extremity of the said shank.

The shank is enclosed by a head indicated at 14, the inner end of the head snugly fitting upon the straight portion of shank 11, while the outer portion of the said head is increased in diameter and is provided at regular spaced intervals throughout its circumference with spaced parallel recesses or 80 openings 15 disposed longitudinally of the head. The recesses 15 extend throughout substantially the entire length of the enlarged portion of the head 14, and the end walls defining these recesses converge or 85 incline inwardly toward the axis of the head.

The blades for the reamer are carried by 90 holders indicated at 16, the latter being applicable to recesses 15, and these holders have their inner or under faces cut at such angle that when resting upon the tapered surface of the shank their outer faces will lie parallel to the axis of the shank. The end walls of the holder 16 are beveled as at 17 to conform to the angularity of the end walls of recesses 15. The outer faces of the tool holders are provided with angular recesses or channels 18 to receive cutting blades 19, and screws 20 threaded through openings 20' in the side walls of the holders engage 100 the sides of the blades 19 and hold the latter firmly in the holders.

The outer extremity of head 14 is reduced as at 21 and exteriorly threaded as shown, and a collar 22 passes loosely over the portion 110

21 and engages the outer ends of the holders 16. The outer portions of the holders 16 at their ends are beveled as at 23, and the inner face of collar 22 is similarly beveled 5 so as to engage the portions 23 of the tool holder. A nut 24 is threaded upon the portion 21 of the head, and an annular compression spring 25 is confined between nut 24 and collar 22. This spring thus exerts pressure 10 upon the lower or outer ends of the tool holders, tending to force the latter inwardly of the shank, and by reason of the coacting beveled faces of collar 22 and the lower ends of the tool holders, the said holders 15 are pressed downwardly into firm engagement with the tapered shank 11.

The head 14 is threaded as at 26 inwardly from its inner end and adjacent the enlarged portion thereof, and this threaded portion 20 receives a nut 27 to engage a collar 28 loosely enclosing the threaded portion and engaging the adjacent ends of blade holders 16. It will be observed that the adjacent edges 25 of sleeve 28 and the blade holder 16 are inclined so that the said collar will tend to press inwardly upon the said holders to maintain the latter firmly seated upon the tapered wall of shank 11.

The head 14 is provided with an elongated 30 recess 29 extending entirely through one wall thereof at the threaded portion 26 thereof, the said recess being disposed longitudinally of the head, and this recess receives a locking key 30 seated in a depression 35 or socket 31 in the shank, and maintained rigidly in position by the screw 32. This key locks the shank and head against relative rotary movement, but permits the said shank and head sliding longitudinally relative to each other.

The inner end of the annular head 14 is provided with an annular recess 33 which receives ribs 34 extending inwardly from the sectional members 35 constituting a two-part bushing (one of the lines of division being between the bushing members being shown in Figure 4), said bushing being confined within flange 36 of sleeve 37 engaged upon threads 12 of shank 11. Screws 38 passing 50 through the flange 36 engage in suitable openings in sections 35 of the bushing, thus holding the flange and bushing together properly assembled upon head 14, and it is obvious from this construction that rotation 55 of sleeve 37 will cause the head 14 to be moved longitudinally upon the shank 11, depending upon the direction of rotation of the said sleeve. The shoulder at the juncture of the portion 36 with sleeve 37 may be 60 provided with graduations as shown at 39 as a guide to the adjustment of the head and its blade holders.

In operating the reamer, the sleeve 37 is rotated in the proper direction to cause the 65 blade holders 16 to be retracted or expand-

ed as desired. As the sleeve 37 is rotated, the rib 34 on annulus 35 will cause the head 14 to move longitudinally of the shank, but rotary movement of the said shank and head relative to each other is prevented by the key 30. As the head is retracted, the holders 16 riding upon the inclined plane provided by the tapered portion of shank 11 will move outwardly, and when the desired projection of the blades is obtained the nut 27 is turned so as to firmly bind collar 28 against the inner ends of the holders while nut 24 may be adjusted so as to bring about the desired pressure upon collar 22. Spring 25 exerts its pressure upon this collar and holds the tool holders against moving or chattering, as the holders are bound firmly upon the inclined surface of the tapered shank 11.

It is noted that the blades 19 are disposed in the tool holders at an inclination to the direction of rotation of the tool in the cutting operation. By so assembling the blades any tendency of the reamer to feed itself during operation is defeated, and tendency 90 to chattering is also obviated.

While the above is a description of the invention in its preferred embodiment, it will be understood that various changes in the minor details of construction and arrangement may be resorted to without departing from the spirit of the invention as defined by the claims.

Having thus fully described my invention, I claim:

1. In a reamer, the combination of a shank having a tapered portion, an annular head enclosing and movable longitudinally upon said shank, said head being provided with longitudinal slots opening through its inner and outer faces, recessed blade holders mounted in said slots and having inwardly projecting extensions with inclined surfaces resting upon the tapered surface of the shank, blades held in the recessed portions of the holders, means for moving the head longitudinally of the shank and fixing it in adjusted position, and means carried by the head for engaging the opposite ends of the blade holders and fixing the same in adjusted position.

2. In a reamer, the combination of a shank having a tapered portion, a head embracing the shank and movable longitudinally thereon, said head being provided with longitudinal and radially extending slots having inclined end walls, recessed blade holders mounted in said slots, said blade holders having portions extending inwardly therefrom and having inner inclined surfaces resting upon the tapered portion of the shank and inclined end portions engaging the end walls of the slots, means for shifting the end walls of the slots longitudinally on the shank and fixing it in adjusted position, collars 120

loosely mounted upon the head and over-hanging and engaging the ends of the blade holders, blades fitted in the blade holders, a nut upon the head engaging one of said collars, a nut upon the head for cooperation with the other collar, and a pressure spring disposed between the latter-named nut and collar.

3. In a reamer, a tapered shank, a head enclosing and movable longitudinally upon said shank, the said head having longitudinal recesses therein, blade holders in said recesses and resting upon said shank, means yieldably maintaining said holders engaged with said shank, and means for moving said head.

4. In a reamer, a tapered shank, a head

enclosing and movable longitudinally upon said shank, a blade holder carried by said head and resting upon said shank, the under 20 face of said holder being inclined similarly to said shank, a collar at one end of said head pressing inwardly upon said holder, a spring engaging said collar, a nut on said head holding said spring, a collar near the 25 opposite end of said head holding the adjacent end of the blade holder, a socket limiting the movement of said collar, and a sleeve threaded upon said shank and engaged with said head, whereby the latter may be moved 30 longitudinally of said shank.

In testimony whereof I affix my signature.

CHARLES A. KELL.
